XEROGRAPHIC BELT LOADING APPARATUS

Eugene C. Ricker, Columbus, Ohio, assignor, by mesne assignments, to Haloid Xerox Inc., a corporation of New York

Original application February 18, 1955, Serial No. 489,250. Divided and this application February 18, 1957, Serial No. 640,930

2 Claims. (Cl. 118—308)

This invention relates in general to xerography and in particular to development of electrostatic charge patterns and is a division of my patent application Serial No. 489,250, filed February 18, 1955.

Xerography uses the physical phenomena of photoconductivity and electrostatic attraction of electrostatically charged bodies to convert a light image into a physical image consisting of, for instance, black powder on white paper. The xerographic plate consists of a film of a photoconductive insulating material on a conductive backing member. In use, the plate is given an electrostatic surface charge and then exposed to a light image, which results in an electrostatic image on the plate surface. This electrostatic image, which may be allowed to remain on the plate or which may be transferred, is developed by allowing it to attract and collect electrically charged particles of powder. The powder image may then be transferred and fixed to another surface, usually a sheet of paper, and the plate may be cleaned for reuse, or the powder image may be allowed to remain on the plate for photographing, viewing, or the like.

One method of image development is known as powder cloud development, and is described, for example, in Carlson U.S. Patent 2,221,776. In this technique of development, a dispersion of powder particles in gas is passed to the surface area bearing the electrical image and properly charged particles are drawn out of the cloud to form a powder deposition in electrical image configuration.

It is an object of this invention to improve upon means and methods for the powder cloud development of electrostatic latent images.

It is also an object of this invention to improve upon apparatus for powder cloud development of electrostatic latent images.

An object in the art of xerography, as in any art concerned with image reproduction, is that of uniformly developing high quality copy. Means of obtaining this objective while using powder cloud development is through the uniform and constant presentation to the electrostatic charge pattern on a surface of a powder cloud of fine developer powder particles uniformly and densely dispersed throughout.

Powder clouds of uniform and dense dispersion of powder particles may be generated by passing a tape or belt of cloth or the like which has been uniformly loaded with powder particles over an output tube at a uniform rate. Particles are blown from the belt or tape in a controlled gas stream, thereby producing a controlled aerosol of uniformly constant and dense dispersions of powder particles. This invention is concerned with the uniform loading of belts, ribbons, and tapes with powder particles and also the end product or the uniformly loaded or impregnated belt, ribbon, or tape of material.

It is, therefore, an object of this invention to devise

new means and methods for impregnating tapes or belts of material with xerographic developer powder particles.

It is yet another object of this invention to devise apparatus for uniformly impregnating belts or tapes of material.

It is still further an object of this invention to devise a new product, a belt, ribbon, or tape of material impregnated with xerographic developer powder particles.

For a better understanding of this invention, together with other further objects thereof, reference is now had to the following description taken in connection with the accompanying drawings, and the scope of the invention will be pointed out in the appended claims.

Figure 1 is an isometric view of an embodiment of a belt, ribbon, or tape stretched between spools.

Figure 2 is a diagrammatic view partially in section of an embodiment of a combination aerosol generator and tape loader.

Figure 3 is a diagrammatic view partially in section of another embodiment of a tape loading device.

For a more thorough discussion of this invention, reference is now had to Figure 1 wherein is shown in detail an embodiment of a belt, ribbon, or tape according to this invention. As appears in this figure, the belt, ribbon, or tape 11 stretches between spool 12 and spool 13. It is to be realized that the object of this invention is the loading of belts and the loaded belt and there is no intent to limit this invention to belts stretched between spools, as shown in this figure.

30 The belt 11 may be loaded or impregnated with xerographic developer powder particles across its entire width, or it may be impregnated or loaded with developer powder particles only across a portion of its width.

An impregnated belt on spools as shown in this figure may be used directly in belt powder cloud generator devices simply by inserting the spools in their proper places in the apparatus and operating the equipment. During operation the belt will move at a uniform rate

40 over an output tube and a constant, steady flow of gas will cause removal of the particles in the belt into a gas stream, thereby creating an aerosol of powder particles. The aerosol may then be conveyed to the development zone for deposition of the powder particles on

45 an electric charge pattern bearing surface. Before deposition, the particles of the aerosol may be charged or deagglomerated, or both, in order to bring about fine grain xerographic development.

Belts may be impregnated with xerographic developer powder particles by brushing the powder by hand into or against the belt, or they may be loaded or impregnated by tumbling the powder over the belt material and scraping off excess powder with a blade or the like. Another technique for loading the belt is that of loading 55 the powder into the material with a spatula or pressing the powder into the material between two surfaces. In the brushing technique, the material is placed on a solid support and large quantities of powder are brushed over the material in all directions with a soft bristled brush. Excess powder is removed by shaking the belt.

Manual techniques for impregnating belts are satisfactory for some applications of loaded belts. For high quality xerographic development, however, it is desirable to eliminate the variables and human elements of error which are present with these techniques. This may be accomplished by using an automatic loading machine in which a uniform aerosol is directed at the belt material as the belt or tape moves at a uniform speed through the aerosol.

Reference is now had to Figure 2 wherein is shown an embodiment of a combination device for automatic

loading of belts. The elements of this combination device are mounted on a support table 15 and comprise generally an aerosol creating mechanism and a belt loading mechanism. The aerosol generator of this figure includes a grooved disc 16, a meter blade 17, an aspirator type pickup tube 18, a tube 20 to supply compressed gas to create aspiration of particles from disc 16 at pickup tube 18, drive means comprising a motor 21 connected to the base of the grooved disc 16 by axle 22 which causes rotation of disc 16 through a gear wheel positioned against the gear wheel of the axle of disc 16. A supply of compressed gas is carried to the equipment through input tube 23 and then through regulating valve 25 to tube 20. As shown, tube 20 carries the compressed gas from regulating valve 25 to the aspirating pickup tube 18.

During operation of the aerosol generator, a supply of xerographic developer powder particles 26 is positioned against meter blade 17. The motor, when operated, causes rotation of disc 16 around its center by rotation of axle 22 causing rotation of axle 27 of the grooved disc. The top surface of grooved disc 16 is uniformly grooved. As the grooves move beneath the supply of developer powder particles 26, they become loaded with powder particles. Meter blade 17 acts to meter a predetermined amount of particles to the surface of disc 16 as portions of the surface of disc 16 move beneath meter blade 17. Particles are then carried by the rotating disc beneath aspirator tube 18 where they are drawn up into pickup tube 18 and are carried to the output point of the aerosol generator.

The output of the aerosol generator is fed to a belt loading zone which in this embodiment is shown as a cylinder designated 37. This cylinder comprises an enclosed but hollow cylinder having an open slot 39 at the top and an entrance point at the base. The output tube of the generator connects to the entrance point at the base and conveys the created aerosol from the aerosol generator to the interna of the cylinder. A tape of material 28 passes over the cylinder and thus over the slot and powder from within the cylinder passes to the tape material as it leaves the cylinder. It is to be realized that the belt loading zone could comprise a cylinder having more than one slot at the top. The tape is supplied from supply spool 30 and is carried to take-up spool 31. The path of tape 28 is from supply spool 30 over first guide rod 32, then over first guide napping rod 33, then over tension rod 34 which operates to position the belt against brush 40, then over second guide napping rod 35, then beneath second guide rod 36, then over loading cylinder 37, then around drive capstan 38 to take-up spool 31. Napping brush 40 is shown positioned to contact tape or belt 28 and brush up a nap on the surface of the tape material at a point between first guide napping rod 33 and second guide napping rod 35. An exhaust duct 41 is positioned above the loading or coating cylinder 37 to pick up and convey away from the mechanism the powder particles which pass through tape 28 at the point of loading.

A motor is connected to drive capstan 38. Motor 21 illustrated in this figure may be used connected through gears or the like to cause rotation of drive capstan 38. The outer surface of capstan 38 is a roughened surface and the belt material is held in close contact thereto and driven or caused to move when capstan 38 is rotated. A clutch mechanism may also be inserted in the connection between capstan 38 and its driving motor 21 so that operation of the aerosol generating equipment may take place without operation of the tape loading mechanism. It is to be realized, of course, that a separate motor may be used to drive capstan 38. A motor may be used to cause napping brush 40 to rotate, and, as in the case of capstan 38, the driving motor may be motor 21 or a separate motor connected directly to napping brush 40. A friction braking mechanism is applied to

the axle of supply spool 30 and a slipping drive friction clutch is applied to take-up spool or reel 31. The friction slipping clutch and friction braking mechanism act to hold tape 28 taut while in position over the different guide rods and the coating cylinder. The friction slipping clutch may be connected between the axle of take-up reel 31 through gears to the motor operating drive capstan 38, or it may be driven by other driving means.

When the tape loading mechanism is operated, drive capstan 38 is caused to move at a uniform speed, thereby imparting uniform speed to the tape material. Although the speed of rotation of take-up reel 31 varies with the amount of material already loaded to the spool, the take-up reel 31 driven by a motor through a slipping clutch 15 winds up as much material as is supplied to it. The braking mechanism on supply spool 30 allows only that much tape to unwind as is caused to unwind by the rotation of capstan 38. Supply spool 30 thereby allows a uniform amount of tape material to pass through the 20 path provided for tape 28, although supply spool 30 rotates at varying speeds depending on the amount of tape on the spool. The napping brush 40 rotates in this embodiment against a surface of the tape, thereby imparting nap to the material. The napped surface of tape 28 is then carried in contact with coating cylinder 37 and over the slot in cylinder 37. Means may also be inserted in a combination device to brush against and thereby impart nap to the other surface of the tape. The powder output from the aerosol generator carried to 30 coating cylinder 37 is blown into and through tape 28. Particles which pass through tape 28 at the point of coating are withdrawn by exhaust duct 41 and the loaded or impregnated tape is wound up on take-up reel 31.

The supply of gas supplied to the regulating valve 35 through input tube 23 in Figure 2 may be from any source of compressed or pressurized gas, such as, for example, an air pump or like pressure generating member, or a suitable pressurized gas container. Such containers are readily available on the commercial market 40 in the form of gas capsules of carbon dioxide or the like under pressure, in the form of bombs or the like of gas such as fluoro-chloro-alkanes, which are available under the general family name of Freon. Similarly, a suitable system may comprise a pump or generating means optionally in combination with a pressure chamber whereby fluctuations in pressure may be limited or avoided.

Reference is now had to Figure 3 wherein is shown a detailed view of another embodiment of a tape loading mechanism. A supply spool 42 supplies the tape 43 for loading purposes. The tape passes over coating cylinder 45 and then beneath drive capstan 46 to take-up reel 47. A motor 48 is connected to drive capstan 46 causing rotation of capstan 46 thereby imparting motion to tape 43. A supply of powder particles in an aerosol is supplied to 55 input tube 50 and the particles are carried along the tube length and through coating cylinder 45 to the output slots 44 at the top of cylinder 45 at which point particles are impregnated into belt 43. A friction slipping clutch mechanism 49 causes take-up spool 47 to take up as much belt as is caused to move to it by the rotation of capstan 46. A friction braking mechanism 51 on supply spool 42 limits the freedom of rotation of this spool and allows only that much belt demanded by the rotation of capstan 46 against the belt material to move from supply spool 65 42. Means other than the braking mechanism 51 may be employed to hold the tape taut such as a flat spring to apply tension against the tape or other mechanism generally known to those in the art.

In this figure the napping element or the napping 70 brush, which appeared in Figure 2, does not appear. The tape or belt material used for loading in this figure in one which either has been pretreated by napping or the like or is one which does not need such pretreatment. Input tube 50 is fed with an aerosol of xerographic developer powder particles. The aerosol could be created

using a generator similar to the one shown in Figure 2, or other similar devices to create aerosols of powder particles could be used.

For proper operation to produce uniformly loaded belts, it is desirable to supply a uniformly dense and uniformly constant aerosol of powder particles to input tube 50. It is also desirable to cause belt 43 to move at a uniform rate over the slots in coating cylinder 45. When these elements are present, a uniform aerosol of powder particles is constantly presented to a section of belt for loading purposes, resulting in a uniformly impregnated or loaded tape, ribbon, or belt of material which may then be used in generating aerosols of xerographic developer powder particles.

Coating cylinder 45 is preferably a hollow cylinder having a smooth outer surface and at least two openings. One opening is needed for the input tube. The other opening or openings comprise the output slot or slots. Smoothness of the outer surface is desirable so that as little resistance to movement by belt 43 in contact with it as is possible is attained, thereby facilitating smooth movement by belt 43 at a uniform linear speed. The cylinder acts as an expansion chamber and it is presently believed that a plurality of output slots makes for a more uniform coating of the belt. The hollowness of the cylinder, also, it is believed, creates a type of swirling action of the powder particles presented from the input tube 50, and this action tends to deagglomerate particles before they are presented to the belt for loading purposes. It is to be realized, however, that belts may be loaded directly without passage of the aerosol through such an expansion chamber.

In impregnating or loading belts, it has been found that belt materials accept powder to a saturation point. Particles carried to the material above the saturation point or slightly past saturation adhere only slightly to the material and may be shaken loose.

To assure uniformity in belt loading, it is sometimes desirable to load to saturation. This is so, for example, when uniformity in the output of the aerosol generator fed to the loading zone is questionable. It is to be realized, however, that belts may be loaded well below the saturation point by passing a belt or tape through the loading zone at high enough speeds to avoid loading to the saturation point or by using a thin aerosol in impregnating the belt material.

Using an automatic loading machine, it is possible to saturate the belt material with powder particles by passing the belt through the aerosol one time or a number of times. More load per belt will naturally result using the same aerosol when the belt is passed through it at the same rate of speed a greater number of times. However, when belt saturation is reached, powder particles will tend to no longer form as part of the belt material and although some particles may deposit on areas of the belt, these particles may be removed to assure uniformity in load throughout by shaking the belt or the like.

An important consideration in forming belts for high quality xerographic reproduction is the belt material itself. The material should be uniform throughout. This will assure presentation to the aerosol of powder particles, for loading purposes, of a material which is at all points able to hold the same amount of particles and also a material which presents the same resistance to the flow of the particles in the aerosol. The belt material may be any porous material which will allow the gas of the aerosol to pass through. At the same time the material should be a material which will tend to hold particles by withdrawing them from the aerosol. A study has been made of various cloth and cloth-like materials which could be used as material for the tape or belt. A summary of this study appears in Table I. The technique used in arriving at powder laden samples to find the data for this table was that of tumbling the powder over the

material and scraping off any excess powder with a blade. The technique used is similar to the manual impregnation techniques mentioned previously in this application. It is to be realized, however, that the data obtained are indicative of data obtainable when using automatic loading techniques, as have been discussed herein.

Table I

	Material	Amount of powder held, gm./sq. in.	Material	Amount of powder held, gm./sq. in.
10	Velveteen	0.062	Wool jersey	0.013
	Woolen coating	0.042	Filter paper, Whatman No. 1	0.011
15	Napped rayon lining	0.040	Mercerized cotton	0.016
	Cotton flannel	0.030	Novelty weave wool	0.007
	Cotton terry cloth	0.025	Cotton broadcloth	0.006
	Miracloth	0.015		

This table indicates that materials having considerable nap are most effective in holding powder. It is to be understood that the materials listed in Table I are only a sample of materials which could be used to act as belt material for loading purposes as is being discussed herein. Any material capable of accepting and holding powder particles as powder particles are blown to and through it is intended to be encompassed within the scope of this invention. For example, a treated mesh metal screen has been found to work well and other similar materials exist and are intended to be encompassed herein.

20 Napped cotton flannel and equivalent materials are the preferred materials as belt material for loading purposes. It has been found through usage that the output when cotton flannel belt material is used is highly constant, dense and uniform, and it is presently believed cotton flannel or equivalent materials accept a dense and highly uniform load. An equivalent material for cotton flannel would be cotton tape or bias material with a napped surface or napped surfaces. The representation in Figure 2 of a napping brush is intended to convey a 25 method for putting a nap on the surface of cotton tape or bias material, but it is to be realized that other mechanisms for accomplishing this objective are intended to be encompassed by this invention.

30 Although a particular aerosol generator has been shown in Figure 2, there is no intention to limit this invention to that particular generator. The generator included therein is for purposes of illustrating a compact unit including the aerosol generator and the tape loading mechanism, and it is to be realized that other aerosol generators 35 are intended to be included in this invention.

40 A number of aerosol generators exist and are known generally to the art. One such generator, for example, comprises an endless belt positioned within a housing. A supply of developer powder particles is positioned at 45 the base of the housing and the endless belt is caused to move through the supply of powder particles. The belt is next led following movement through the particles to an output tube. At the point of the output tube the belt is drawn tautly over the internal opening of the output tube, and gas moving through the housing moves through the belt carrying powder particles, thereby creating at 50 the output end of the device an aerosol of xerographic developer powder particles. Another type of powder cloud generator which may be used to create the aerosol 55 of xerographic developer powder particles to feed to the tape loading mechanism comprises a housing enclosing a disc on which is positioned a supply of developer powder particles. A blade holds the supply of developer powder particles in place and the disc is rotated beneath the 60 powder particles. The blade meters a uniform amount of powder particles to areas of the disc passing therebeneath. The metered supply of powder particles is then carried to an area where the output is created. In one 65 type of generator, the output is taken from the housing by gas rushing from within the housing through the disc

70

75

and into an output tube pressed firmly against the disc material. In another case, the output tube is positioned slightly above the disc and as gas from within the housing rushes out the output tube, it entrains the powder particles positioned on the disc beneath the output opening. The output from either of these last two generators could be fed to a tape loading mechanism as illustrated in Figure 3 and in Figure 2 for purposes of impregnating or loading tape or belt material. It is to be realized that it is not intended to limit this invention to the generators discussed above or the generator shown in Figure 2. These generators have been discussed for illustrative purposes, and it is intended to include within this invention the many possible mechanisms and means for generating aerosols of powder particles which may be fed to the tape loading mechanism.

From the point of view of composition of the developer particles in the aerosol fed to the tape or belt material for loading, prints or pictures may be produced with belts or tapes loaded or impregnated with charcoal, carbon blacks, or carbonaceous pigments. Under proper conditions, any of a number of various carbon or lamp black materials may be employed, including such material as furnace blacks, channel blacks, and the like. In addition, there may be used such material as milled charcoals and similar materials, or, if desired, finely divided materials having added pigment matter. In the latter category are materials such as finely divided resins containing pigments or dyes such as carbonaceous pigments or various coloring pigments and the like, compositions of this type being preferred where the print or picture ultimately is to be made permanent by a fusing process including heat or vapor fusing. For highest quality work the presently preferred material is milled wood charcoal.

A number of generalities apply in carrying out this invention. For example, aerosols of powder particles of different densities may be efficiently used in loading tapes and in creating impregnated belts according to this invention. If a particular load in a belt is desired, such a load may be attained either when using a thin aerosol or a very dense aerosol. Other means of control exist. For example, the belt or tape may be made to move over the loading cylinder at a rapid pace or a slow pace. This may be accomplished through the use of a variable speed driving motor. Also, it is possible to reload a loaded belt. This fact is pertinent, in that if a particular linear speed of movement of the tape material is desired, a particular load may be attained by cycling the belt or tape material over the loading zone one or many times, depending upon the aerosol of powder particles being supplied to the belt material.

Another generality relates to air flow at the loading zone and pressures through the generator system and to and through the input tube of the tape loading mechanism. The desire is to produce an aerosol which will impregnate or load a tape or belt of material. When too high an air flow is used, insufficient loading of belt or tape materials results. When too low an air flow is used, the tendency again is for partial and inefficient loading to take place. Particles in such an instance are not blown throughout the thickness of the belt, but tend to stop as they strike the cloth. However, uniformity in density of cloud presented to the belt will produce a uniformly loaded belt of material. Good belts have been obtained using air flows at the loading zone ranging from .1 c.f.m. to 25 c.f.m., free air flow, and belt loading will result using a broader range of free air flow at the loading zone. The pressure of the system and through the tubes supplying the aerosol of powder particles to the tape loading mechanism may also vary substantially. A general range for good loading is from 0 to 4 p.s.i., but it is to be realized that a broader range than this may be used and valuable results will still be obtained for use in the xerographic art.

The linear speed of the tape may also vary within a substantially large range. Very good results for high quality prints are obtained when loading with a proper aerosol at anywhere from .08 inch per second to 4 inches per second linear speed of the tape. However, good quality prints may be obtained from tapes which have been loaded within a substantially broader range. For example, it is believed a tape can be loaded at 100 inches per second.

10 In the preferred embodiment of this invention, developer particles are supplied mixed in air to the loading apparatus under a pressure of 4 p.s.i. at a rate of 1½ cubic feet per minute, carrying in the mixture 1.3 grams per cubic foot of gas. The belt is loaded at a rate of 15 1 foot per minute and when loaded is impregnated with 120 mgms. of developer powder per foot of belt when the width of the loaded area is ½ inch. The particular belt material in this embodiment is white medium weight cotton flannel 4 ounces per square yard. The amount 20 of powder impregnated into the belt is approximately ½ of the powder flowing to the belt loading apparatus. The other 95% is spent by remaining in the tube and the cylinder and by being dispersed in air after passing through the belt. In use, four inches of belt loaded as 25 per the preferred embodiment is required to develop a fine grain high quality picture on a 4 x 5 plate.

A loaded or impregnated belt is presently believed to have powder extending through all areas of thickness of the belt material. The load accepted by each belt is 30 dependent on the density of the cloth and the ability of the cloth to load with powder particles. By ability of the cloth to load it is intended to include such elements as the effect of the cloth's mesh and the cloth's nap, whereas the density is intended to include the effect 35 of such elements as the thickness of the cloth. Powder loaded or impregnated to the belt deposits both between the threads and on threads and between areas of napped material and on the napped material. Belt materials, it is presently believed, have a saturation point above 40 which they tend not to accept within themselves any more developer powder particles. Although powder particles may be fed to the belt material and although such particles may occasionally remain resting on the surface, they are easily removed by simply shaking the loaded belt. Thus, it is believed that particles above the saturation point of the belt will shake loose; whereas those particles below the saturation point which have become 45 part of the belt material will remain adhering to the belt material.

50 Belts described according to this invention, when used in powder cloud generators, have the advantage of consistency and uniformity between belts with similar characteristics. Two belts of similar material loaded with a similar aerosol at the same rate of speed will produce 55 highly consistent and uniform cloud outputs when used in similar powder cloud generators. Also, it has been found that since belts tend to stop loading at what is believed to be a saturation point, the aerosol fed to the belt or tape material need not be highly uniform, and 60 yet a belt will be produced which when used with a powder cloud generator will deliver a consistent and uniform aerosol of powder particles. Belts also have the advantage of being able to produce fine and high quality aerosols of xerographic developer powder particles which 65 may be used directly for development purposes without other elements between the powder cloud generator and the development zone such as settling chambers or the like. Another advantage of belts loaded according to this invention is that they are compact and also they 70 may be stored, producing convenient sources of powder for powder cloud generators to be called upon when needed.

While the present invention as to its objects and advantages, as has been described herein, has been carried 75 out in specific embodiments thereof, it is not desired

to be limited thereby, but is intended to cover the invention broadly within the spirit and scope of the appended claims.

What is claimed is:

1. A device to impregnate tapes with releasable xerographic powder particles comprising a powder cloud generator for creating an aerosol of xerographic developer powder particles, a hollow enclosed cylinder, a powder cloud conduit connecting said powder cloud generator to said cylinder, a longitudinal slot opening in said cylinder to provide an exit for said powder particles from said cylinder, and tape transport means positioned and adapted to uniformly move a permeable napped tape material past said slot and in contact with and transversely covering said slot while the aerosol of xerographic developer issues from said slot.

2. A device to impregnate tapes with releasable xerographic powder particles comprising a powder cloud generator for creating an aerosol of xerographic developer powder particles, a hollow enclosed cylinder, a powder cloud conduit connecting said powder cloud generator to said cylinder, a longitudinal slot opening in said cylinder

5 to provide an exit for said powder particles from said cylinder, and tape transport means positioned and adapted to uniformly move a permeable napped tape material past said slot and in contact with and transversely covering said slot while the aerosol of xerographic developer issues from said slot, and napping means positioned with respect to said transport means to impart a surface nap to the surface of said tape which moves into surface contact with said cylinder before said tape passes across said

10 slot.
